UNITED STATES PATENT OFFICE

2,685,805

METHOD OF MAKING BLANKING DIES

John R. Baumgartner, Milwaukee, Wis.

Application February 6, 1953, Serial No. 335,515

2 Claims. (Cl. 76—107)

1

The invention relates to a method of making the cutting and creasing dies or blanking dies for a blanking press for forming carton blanks.

The main object of the invention is to provide a method for making dies of the character above described whereby any set of dies may be used interchangeably on several presses and whereby any set of dies may be made and furnished to a press owner without having to use the press, on which the dies are to be mounted, as a proofing press.

The invention further consists in the several steps of making the dies as hereinafter more particularly described and claimed.

In the drawings:

Fig. 1 is a side elevation view of a carton blanking and creasing press, parts being broken away;

Fig. 2 is a plan view of a male die chase;

Fig. 3 is a plan view of this chase with a drilling jig superimposed thereon;

Fig. 4 is a detailed vertical sectional view taken on the broken line 4—4 of Fig. 3, parts being broken away;

Fig. 5 is a detailed vertical sectional view taken on the line 5—5 of Fig. 3;

Fig. 6 is a vertical sectional view through a portion of a male die with a locating pin in place;

Fig. 7 is a view similar to Fig. 3 showing the jig used in Fig. 3 applied to the counterplate or female die;

Fig. 8 is a detailed vertical sectional view taken on the line 8—8 of Fig. 7;

Fig. 9 is a detailed vertical sectional view taken on the broken line 9—9 of Fig. 7;

Fig. 10 is a plan view showing the counterplate superimposed on the male die chase;

Fig. 11 is a detailed vertical sectional view taken on the broken line 11—11 of Fig. 10;

Fig. 12 is a plan view of the counterplate as marked by rules of the male die chase;

Fig. 13 is a plan view of the counterplate after milling the creasing grooves therein;

Fig. 14 is a detailed vertical sectional view taken on the line 14—14 of Fig. 13;

Fig. 15 is a plan view of a completed male die;

Fig. 16 is a vertical sectional view through a pair of aligned dies temporarily held together;

Fig. 17 is a plan view of the base plate for the counterplate with an adhesive applied thereto;

Fig. 18 is a view of the dies as shown in Fig. 16 and the counterplate base plate set up in the press for transfer of the counterplate to its base plate;

Fig. 19 is a view similar to Fig. 18 showing the counterplate transferred to its base plate;

2

Fig. 20 is a bottom plan view of the inverted counterplate and base plate after drilling the locating holes in these plates;

Fig. 21 is a detailed vertical sectional view taken on the line 21—21 of Fig. 20;

Fig. 22 is a view similar to Fig. 21 with a locator pin in place;

Fig. 23 is a top plan view of the counterplate and base plate assembled together;

Fig. 24 is a detailed vertical sectional view taken on the broken line 24—24 of Fig. 23;

Fig. 25 is a view similar to Fig. 24 showing a portion of the finished lower die;

Fig. 26 is a view of a counterplate as adapted for use on any of a plurality of machines;

Fig. 27 is a detailed sectional view taken on the line 27—27 of Fig. 1.

In the carton blanking and creasing art it has been the usual practice to furnish cutting and creasing dies for the blanking press of each individual machine so that a user could not use these same dies on another similar machine because no two press structures are identical, but the dies must accurately align with each other for satisfactory work. These dies are very expensive

because of the time and labor involved in their construction so that there is decided advantage in having the same set of dies available for one or more presses and in having a set of dies which may be supplied to the user for any similar press.

By the method hereinafter described a set of dies may be prepared for use on any one of a number of similar presses, and the owner of these presses by a relatively simple procedure of mounting the counterplate to a baseplate therefor for each machine may use the same set of dies on several similar presses, or he may order a set of additional dies for any press and readily mount these dies himself on the press.

Referring to the drawings, I have shown in Fig. 1 a portion of a carton blanking press which includes a fixed platen 28 carrying a male die M having a base 29 and a reciprocatory platen 30 carrying the female die F, this die comprising a counterplate 31 and a base plate 32. The web W of carton stock is fed in between the dies M and F, and then the platen 30 is raised to press the web between the dies to form the cuts and creases for the carton blank.

The dies M and F are removably mounted on and clamped to their respective platens in known manner. As indicated in Fig. 1, the bases of each of the dies has a bevelled edge 33 that abuts a bevelled rail 34 on the platen against which it is tightly wedged by wedge bolts 35 engaging

the opposite bevelled edge 36 of the base plate. Each die is also held against movement in the opposite direction on its plate by any suitable lock as the locking lever 37 pivotally mounted on the platen and engageable with a pin 38 on the handle 39 of the die.

As a step in the method, a chase for the male die M is formed as shown, for example, in Fig. 2, this chase including the base 29 which is recessed to receive the male spacers 40 which include the strips and blocks that are held to the base plate by screws 41 and are accurately located by temporary rules 42 filling these spaces which the creasing and cutting rules will occupy in the finished die, and a recess 43 is formed in one of the strips.

A jig J including a flat plate 44, and accurately located bushed holes 45, and bevelled locator pins 46 alined therewith and a third locator pin 47 is then placed over the chase so that the bevelled locator pins 46 abut the bevelled edge 36 of the base 29 and the pin 47 is disposed in the recess 43 to abut the side of the large block receiving recess formed in the base 29, which side is at right angles to the edge 33 as shown in Figs. 3 and 5. The parts thus superimposed are held together while holes 48 are drilled in the frame 29 using the bushed holes 45 as guides for the drill, see Fig. 4. Locator pins 49 are then mounted in the drilled holes so that the die M now has two points of alinement which are parallel to the bevelled edge 33 that will abut the fixed rail 34 in the press.

The jig J is then taken and superimposed on a flat hardened metal plate, forming the counterplate 31, but the bevelled locator pins 46 are replaced by flat sided locator pins 46a which abut one side edge of the plate while the pin 47 of the jig abuts the side of the plate at right angles thereto as shown in Figs. 7 and 8, and with these parts firmly held together locator holes 50 are then drilled in the plate using the bushed holes 45 of the jig as drill guides. At the same time a series of small holes 51 are drilled in the plate using the small holes 52 in the jig as guides.

After some of the temporary rules 42 are removed from the die M and replaced by creasing rules 53, as indicated in Fig. 11, the drilled counterplate 31 has one of its sides coated with a suitable transfer ink or paint and is then superimposed upon the male die M as shown in Figs. 10 and 11 and accurately located relative thereto by mounting the upper portions of the pins 49, then in the die M in the locator holes 50 in the counterplate, so that when the coated side of the plate 31 is brought down into contact with the upper edges of the creasing rules 53, these rules will make an impression or marks on this side of the plate 31 as shown in Fig. 12 which may be used as a guide pattern or patterns P for forming the relief grooves 54 for these rules in the plate 31. The plate 31 is then removed from the die M and the grooves 54 are, where the plate is of metal, milled in it to conform to the pattern transferred to it from the male die M.

With each machine furnished the user, the manufacturer supplies the counterbase plate 32 which has two locator counterbored holes 55 formed therein at opposite corner portions (see Figs. 20 and 21). The position of these holes 55 on the plate 32 is different for each machine furnished the user so that for one machine the holes 55 will be located as shown in full in Fig. 20 and for another machine these holes will be

located as indicated in dotted lines in this figure. Temporary bushings 56 are mounted in the holes 55, and these after drilling the counterplate 31 as hereinafter described are replaced by shouleder locating pins 57 that fit the counterbored holes 55.

The accurately located counterplate 31 and the finished die M is also furnished by the manufacturer, an example of which is shown in Fig. 15 which in addition to the creasing rules 53 includes the cutting rules 58. As shipped, the die M may be supplied with pads 59 of cork or other suitable filler material, and similar material may be removably mounted as strips 60 adjacent the cutting rules 58.

The final installation of the die parts noted above as furnished by the manufacturer is done by the user. The pad portions 59 are covered with pieces of flexible material 61 coated on both sides with adhesive and indicated in Fig. 16. The finished counterplate 31 is laid over the top of the die M in contact with the exposed sticky side of the material 61 and with the pins 49 projecting through the locator holes 50, and the male die with the attached counterplate 31 is then clamped in the upper fixed platen 28 of the press, and the base plate 32 furnished with the machine, after having a sheet 62 of adhesive material applied to its top face, is mounted in the movable platen 30 of the machine as shown in Fig. 18. Then the platen 30 is raised to bring the adhesively coated base plate 32 into contact with the bottom face of the plate 31 and then lowered carrying the plate 31 with it as shown in Fig. 19 since its adhesive coated area is greater than that used to initially hold the counterplate 31 to the die M. The adhesively united plates 31 and 32 are then removed from the press and the base plate 32 turned bottom side up as shown in Fig. 20. Using the bushed holes 55 as guides, holes 63 are then drilled in the counterplate 31 as indicated in Fig. 21 and then the bushings 56 are removed and replaced by the locating pins 57 as shown in Fig. 22. The counterplate 31 which by the manufacturer has already been accurately located relative to the die M by the pins 49 and holes 50 and been accurately located relative to this die in the press by the user as shown in Fig. 18 and transferred to the base plate 32 as above described while in the press is now accurately located on the base plate 32 by the pins 57. The adhesive sheet 62 is then stripped from the plates 31 and 32, and using the pins 57 as locators the plates are brought together and using the holes 51 drilled in the plate 31 as guides, holes 64 are drilled in the base plate 32 (see Figs. 23 and 24). The holes 51 in the plate 31 are then countersunk, and the holes 64 in the plate 32 are tapped to receive the flat head screws 65 as shown in Fig. 25. The pins 49 and adhesive 61 are removed from the die M, and the dies are now completely ready for use in the press.

If the press owner wants to use the dies on another similar machine, all he has to do is to remove the counterplate 31 from the base plate 32 of the first machine and following the procedure above described place the die M and the counterplate 31 on the second machine and relocate the counterplate 31 on the base plate 32 of that machine by drilling a new set of locator holes 63 in the counterplate. Thus one set of dies may be used on several different machines and have as many sets of locator holes 63 in it as there are base plates 32 for these machines, it

being noted that in using this same counterplate on several base plates 32 the tapped holes 64 in the base plates need not line up closely with countersunk holes 51 of the counterplate since the screws 65 are not for alinement purposes but merely to hold the plate 31 to their associated base plate 32. Fig. 26 shows a plan view of a counterplate as adapted for use on a plurality of machines.

It is also to be noted that since the machine owner does the final installation of the counterplate on its associated base plate, that the owner may order a set of new dies for any of his machines, and these dies comprising the male die M and the matching counterplate 31 can be supplied to him by the manufacturer without the manufacturer requiring the use of the press as a proofing press.

It will be noted from the foregoing description that the essential features of the method consist in making a male die and counterplate with alining means so that these dies can be accurately located together while on the press, then transferring the so located counterplate to the top of its base plate while in the press, then using the base plate as a jig for drilling locator holes in the counterplate so that locator pins mounted in the jig holes of the base plate and projecting into the locator holes in the counterplate will maintain the alined association of this counterplate with the male die when the dies are used in the press.

What I claim as my invention is:

1. The method of making a set of dies for a blanking press which comprises making up the chase for a male die having an edge adapted to abut a rail on the platen of the press, using this edge and a point at right angles thereto as locators and applying a jig having locator holes to the chase and drilling locator holes in the chase, placing temporary locator pins in these holes, taking this same jig and alining it with an edge of a counterplate and using the same locator holes in the jig as guides drilling locator holes in the counterplate, coating one side of the counterplate with a transfer medium and superimposing this coated plate upon the chase having its creasing rules mounted therein while its locator holes are alined with temporary locator pins to secure an impression of the pattern of the rules on the plate, removing portions of the plate defined by said pattern to provide creasing recesses,

mounting the cutting rules in the male die to finish the die then adhesively uniting the male die with the counterplate in pinned alined relation thereto and mounting the male die on one of the press platens and taking a base plate for the counterplate and mounting it in the other platen of the press, said base plate having an adhesive coating of greater area than that adhesively uniting the counterplate to the male die, moving the press platens relative to each other to bring the base plate into adhesive contact with the counterplate on the die and then moving the platens relative to each other to transfer the counterplate to the base plate, removing the base plate with the counterplate adhesively attached thereto from the press, establishing fixed points of alinement between said counterplate and said base plate, and securing said counterplate to said base plate in its alined relation therewith.

20 2. The steps in the method of making a set of dies for a blanking press which comprise adhesively uniting the male die with its cooperative counterplate in pinned alined relation thereto and mounting the attached die on one of the 25 press platens, taking a base plate for the counterplate and mounting it in the other platen of the press, said base plate having an adhesive coating of greater area than that adhesively uniting the counterplate to the male die, moving the 30 press platens relative to each other to bring the base plate into adhesive contact with the counterplate on the die and then moving the platens relative to each other to transfer the counterplate to the base plate, removing the base plate with the 35 counterplate adhesively attached thereto from the press, establishing fixed points of alinement between said counterplate and said base plate, and securing said counterplate to said base plate in its alined relation therewith.
